METHOD AND APPARATUS FOR METAL
COATING TUBING

Rea I. Hahn, Rochester, N. Y., assignor to General Motors Corporation, Detroit, Mich., a corporation of Delaware

Application October 31, 1950, Serial No. 193,266

18 Claims. (Cl. 117—114)

1

This invention relates to the coating of metal articles with a metal of lower melting point than the article to be coated, and more particularly to a method of and apparatus for coating either single-ply welded tubing or two-ply brazed tubing with a metal of lower melting point than the metal of the tubing.

An object of the invention is to facilitate the use of brazing or coating metal in a manner which avoids wasting it. To accomplish this object, disclosed embodiments of the invention comprise a crucible into which the brazing or coating metal is introduced, preferably as a wire, and an electrical coil surrounding the wire which is connected with an alternating current source of relatively high frequency, for example, at 400 volts and 960 cycles, when the coating metal is copper, such coil being capable of transmitting electrical energy sufficient to melt the coating or brazing metal in the crucible and to cause said metal to be projected in the crucible, above the article to be coated, as a mound of molten metal through which such article is passed horizontally to receive metal for brazing or coating purposes. There is an enclosed chamber above the metal in the crucible into which reducing gas under pressure is introduced through ducts provided by wiper blocks through which the article to be coated passes in order to remove excess molten metal from said article and return the excess to the crucible and to provide an atmosphere in which oxidation of the article and the metal does not occur.

As described specifically herein the method and apparatus disclosed is employed to coat single-ply welded tubing or braze multi-ply tubing, but it should be apparent that the method and apparatus described can be used just as well to coat other articles, for example, a wire, a rod, or any other form of metal tubing.

Further objects and advantages of the present invention will be apparent from the following description, reference being had to the accompanying drawings, wherein preferred embodiments of the present invention are clearly shown.

In the drawings:

Figs. 1 and 2 constitute a plan view of a mill for making two-ply, copper brazed, steel tubing.

Fig. 3 is a plan view of brazing apparatus 20 shown diagrammatically in Fig. 2.

Fig. 4 is a sectional view on line 4—4 of Fig. 3.

Figs. 5 and 6 constitute a diagram of a mill for making coated, welded steel tubing.

Fig. 7 is a longitudinal sectional view of the

2

coating apparatus 130 of the mill as shown in Fig. 4.

Two steel strips S which move toward the left in Fig. 1 pass between pairs of scarfing rolls 10 and 11 which bevel the edges of the strip. The strips then pass through a lubricating device 12 and between pairs of rolls 13 of a former 14 which progressively shape the strips into a tube T in the manner shown in the patent to Nichols and Bish #2,195,751 dated April 2, 1940.

The tubing passes through a swedger 15 which compacts the plies of the tubing. Then the tubing passes left in Fig. 2 between pairs of electrode rolls 17 and 18 of a preheater 16 connected with a current source for the purpose of heating the tubing before it passes to the apparatus 20 for applying molten copper thereto to braze the plies of the tubing. After brazing the tubing passes through a cooler 60 having a jacket 61 through which water circulates. Then the tubing is wound on a reel 62 driven by a power mechanism 63 for the purpose of pulling the tubing through the brazing apparatus 20 and the cooler 70.

Referring to Figs. 3 and 4, the brazing apparatus 20 comprises a non-conducting base 21 supported above the floor by a frame 22 and supporting brackets 23 and 24 which support a refractory plate 25 having grooves 26 and providing a central opening 27 giving access to a refractory crucible 28 enclosed by a heat insulating body 29 supported by the plate 21 and surrounded by a non-conducting tube 30 surrounded by a shorter-conducting tube 31. Tube 31 supports a coil 32 of flattened copper tubing having round ends 33 and 34 connected respectively by wires 35 and 36 with an alternating current source, for example, at 400 volts and 960 cycles when the brazing metal is copper. Heat is conducted away from the coil 32 by the circulation of water through the coils. For this purpose the coil ends 33 and 34 are connected with non-conducting hoses 37 and 38. Coil ends 33 and 34 are supported by a non-conducting block 24a which screws 24b secure to bracket 24.

The opening 27 in plate 25 is closed by a refractory cover 40 having a hole 41 closed by a glass block 42 and having a hole 43 through which a copper wire is moved downwardly. The grooves 26 of plate 25 support metal blocks 45 providing aligned holes 46 through which the tubing T passes from right to left. Each block 45 provides an inclined duct 47 connected by pipe 48 and a hose 49 with a source of reducing gas under pressure. Blocks 45 are retained with-

in grooves 26 by clips 50 which screws 51 attach to the blocks and which are attached to brackets 23 and 24 by screws 52. A non-conducting jacket 53 supported by a plate 21 surrounds the coil 32 and the sleeve 31.

The high frequency A. C. current flowing through the coil 32 effects the melting of the copper wire as it is fed downwardly into the crucible and causes the metal in the crucible to be projected upwardly as indicated by the dot-dash line 54 to form a mound of molten metal through which the tubing T passes while in an atmosphere of reducing gas flowing from the ducts 41. The metal readily wets the surface of the tubing and flows along it and the excess is wiped off and returned to the crucible 28 by the jets of compressed reducing gas issuing from the ducts 41. The amount of electrical energy used by the apparatus for melting the copper and for causing upward projection thereof is preferably about 20 kva. of which about $\frac{1}{4}$ is used to melt the copper, the excess of the heat generated being absorbed by the tubing which is maintained, while within the apparatus 20 at a temperature above the melting point of copper. Since the tubing is pre-heated by the apparatus 16, its rate of movement through the apparatus 20 can be increased because the preheating supplies a substantial portion of the heat units required to elevate the temperature of the tubing above the melting point of the metal in the crucible 28.

A modified form of the apparatus 20 can be used in the coating of welded steel tubing produced by a mill shown in Figs. 5 and 6. A strip of metal S moving left in Fig. 5 is progressively formed by pairs of rolls 110, 111, 112 and 113 into a tubing T having a butt seam which is welded as it is urged against spaced electrode rolls 114 by a back-up roll 115 supported by a lever 116 pivoted at 117 on a bracket 118 and urged upwardly by constant pressure applied by compressed air within a bellows 119 mounted on a base 120. A pipe represented by a line 121 extends down between the edges of the strip so that it enters the tubing between the rolls 111 and 112 and then extends horizontally. Through this pipe a reducing atmosphere is introduced into the tubing.

The welding apparatus back-up roll construction constitutes no part of the present invention and may be such as shown in Nichols Patent No. 2,293,846, dated August 25, 1942, and in Hahn et al. Patent No. 2,492,572, dated December 27, 1949.

The bead formed on the tubing during the welding operation is removed by a tool 122. The tubing then passes between pairs of sizing rolls 123 and 124 and then between pairs of electrode rolls 126, 127 and 128 of an annealer 125 having roll housings 126a, 127a, 128a and connecting tubes 129, all enclosing a reducing atmosphere.

The tubing which has been heated by the annealer passes directly to an apparatus indicated at 130 for coating it with a non-corrosive metal such as copper which fills up minute pores in the tubing and provides it with a coating which is rust-proof. The tubing next passes through a cooling pipe 178 which is surrounded by a jacket 171 through which cold water circulates. The tubing is then wound upon a reel 172 which is power driven to take up the slack in the tubing.

Referring to Fig. 7, the apparatus 130 comprises a non-conducting base plate 131 supported above the floor by frame members 132. Base 131 supports metal brackets 133 and 134 which sup-

port a non-conducting plate 135 having grooves 136 and having a central opening 137 providing access to a refractory crucible 138 surrounded by heat insulating material 139 supported by plate 131 and confined within a non-conducting sleeve 140 extending within a non-conducting sleeve 141 which supports a coil 142 of flattened copper tubing having round ends 143 and 144 connected respectively, with insulated wires 145 and 146 with a high frequency alternating current source preferably at 400 volts and 960 cycles. Heat is conducted from the coil 142 by circulating water through it. For this purpose non-conducting hoses 147 and 148 are clamped about the coil ends 143 and 144. These ends are supported by a non-conducting block 134a secured to bracket 134 by screws 134b.

Plate 135 supports a refractory cylinder 150 having a refractory cover 151 supporting a glass plate 152 and having a hole 153 through which a wire W of copper, or other suitable metal, is introduced. A portion of the coil 142 surrounds the tube 150 and is surrounded by a refractory cup-shaped jacket 154 supported by the plate 135.

The grooves 136 of plate 135 receive metal blocks 155 having aligned holes 156 through which the tubing T passes from right to left. The right-hand block 155 supports the tubing as it moves horizontally, but the left-hand block 155 does not support the tubing since all portions of its hole 156 clear the tubing. Each block 155 has an obliquely disposed duct 157 connected by a pipe 158 and a hose 159 with a source of pressurized reducing gas which flows out through the ducts 157 to wipe off excess metal received by the tube and to return the excess metal to the crucible 138. Blocks 155 are retained in groove 136 by clips 160 which screws 161 attach to the blocks and which screws 162 attach to brackets 133 and 134. An insulating tube 163 supported by plate 131 surrounds sleeve 141 and the lower portion of coil 142.

The passage of electric current, for example, 400 volts A. C. at 960 cycles when the coating metal is copper, through the coil 142 causes heating of the crucible 138 and the tube 150 to a high temperature so that the wire W melts as it is fed downwardly. The molten metal of the wire fills the crucible. The passage of high frequency current through coil 142 causes the molten metal in the crucible to rise up as indicated by the curved dot-dash line 164 to form a mound of molten metal through which the tubing passes. As the tubing passes through this mound it receives a coating of the metal which readily wets the tubing since it is in a reducing atmosphere provided by the gas flowing from the ducts 157.

The electrical energy used by the apparatus for melting copper and for causing upward projection thereof is preferably about 20 kva., the minor proportion of which supplies the heat for melting the copper, the excess of the heat generated being absorbed by the tubing at a temperature which is maintained, while in the apparatus 130, above the melting point of the metal in the crucible 138. Since the tubing passes directly from the annealer 128 to the coating apparatus 130, its rate of movement through the apparatus 130 can be increased because the annealer 128 supplies a substantial part of the heat units required to maintain the temperature of the tubing, while in the apparatus 130, above the melting point of the metal in the crucible 138.

When an electric heating means of the character described herein is employed to heat the

copper or other metal employed to braze or coat steel tubing, there is less waste of the coating metal due to the carrying of such metal out of the heating chamber by the moving tubing for the following reason. The level of the coating liquid is raised, above the level of the tubing, by the effect of the high frequency current, only in the area around the vertical axis of the heating chamber, as indicated by the dot and dash lines in Figs. 4 and 7. The level of the coating metal adjacent the wall of the heating chamber is not raised so that the opening through which the tube passes out of the chamber is always above the level of the molten coating metal. Therefore there is no tendency for the moving tubing to drag the coating metal from the main supply outwardly through the exit opening through which the tubing passes. The tubing tends only to carry out of the heating chamber such surplus coating metal as sticks to the tube when it passes through the mound of metal at the central part of said chamber. This is substantially all blown off of the tubing and back into the heating chamber by the gas blast through the pipe or nozzle 48 at the left of either Fig. 4 or Fig. 7.

Both the apparatus shown in Fig. 4 and that shown in Fig. 7 can be used for copper coating welded steel tubing as well as for copper brazing or multi-ply steel tubing. The height of the column, or mound of metal projected above the tubing is a function of the amount of electrical energy which is transmitted by the heating coil. However, the amount of electrical energy which can be employed is limited by the capacity of the moving tubing to remove excess heat as fast as excess heat is generated. If the excess heat is not removed as fast as it is generated, the coating or brazing metal would be overheated. Therefore, the coil cannot be used to transmit more than a certain amount of energy and this determines the height of the mound or column of coating metal which can be obtained.

It should be equally apparent that the device of either Fig. 4 or Fig. 7 can be used to coat other articles than the specific form of tubing referred to with copper or some other metal of lower melting point than the article to be coated. For example, the element designated therein could be a wire, or a rod, or some different form of tubing, and the apparatus disclosed would be just as effective to coat such an article as it is to coat the particular types of tubing previously referred to.

If it is desired to employ a higher mound or column of the molten coating metal during the coating operation, it is desirable to use the form of the device shown in Fig. 7 of the drawings. Since, in the apparatus shown in Fig. 7, half of the heating coil is above the level of the coating metal, the efficiency of the coil is less than in the form of the device shown in Fig. 4 and more electrical energy can be employed without overheating of the metal and a higher column or mound of such metal can be obtained than if the apparatus of Fig. 4 is used. It will be desirable to vary the height of the column of coating metal when different metals are used, such as copper, tin and lead alloys, aluminum or brasses, for example, due to different characteristics and melting points.

While the embodiments of the present invention as herein disclosed, constitute preferred forms, it is to be understood that other forms might be adopted.

What is claimed is as follows:

1. The method of brazing multi-ply metal tubing or coating welded tubing with a metal of lower melting point than that of the tubing which includes the steps of moving the tubing through a chamber containing in the lower part thereof a quantity of the coating metal, while maintaining the tubing at a level above the normal level of the coating metal therein when in a non-molten condition, heating the lower part of said chamber in which the coating metal is contained by subjecting the lower part of such chamber to the heating effect of a high frequency electric current to a degree sufficient to melt such metal and to cause the level of the molten metal in the chamber to rise above the level of the tubing as the latter is moved through the chamber, subjecting the tubing as it leaves the chamber to a blast of non-oxidizing gas directed against the tubing at a point relatively close to an opening through which the tubing moves out of said chamber and introducing the coating metal into the chamber in unmelted form as the tubing is moved through said chamber.
2. The method of brazing multi-ply metal tubing or coating welded tubing with a metal of lower melting point than that of the tubing which includes the steps of moving the tubing through a chamber containing in the lower part thereof a quantity of the coating metal, while maintaining the tubing at a level above the normal level of the coating metal therein when in a non-molten condition, heating said chamber both above and below the level at which the tubing passes through the chamber by subjecting both parts of such chamber to the heating effect of a high frequency electric current to a degree sufficient to melt such metal and to cause the level of the molten metal in the chamber to rise above the level of the tubing as the latter is moved through the chamber, subjecting the tubing as it leaves the chamber to a blast of non-oxidizing gas directed against the tubing at a point relatively close to an opening through which the tubing moves out of said chamber and introducing the coating metal into the chamber in unmelted form as the tubing is moved through said chamber.
3. The method of brazing multi-ply metal tubing or coating welded tubing with a metal of lower melting point than that of the tubing which includes the steps of moving the tubing through a chamber containing a quantity of the coating metal while maintaining the tubing at a level above the normal level of said metal therein, heating the coating metal in said chamber by use of high frequency electric current to a degree sufficient to melt said metal and to cause the level of the molten metal to rise above the level of the tubing as the latter is moved through the chamber so that the tubing passes through the molten metal during its movement and introducing the coating metal into the chamber in unmelted form during the passage of the tubing through said chamber.
4. The method of brazing multi-ply metal tubing or coating welded tubing with a metal of lower melting point than that of the tubing which includes the steps of moving the tubing through a chamber containing a quantity of the coating metal while maintaining the tubing at a level above the normal level of said metal therein, heating the lower part of the chamber in which the coating metal is contained by use of a high frequency electric current to a degree

sufficient to melt said metal and to cause the level of the molten metal to rise above the level of the tubing as the latter is moved through the chamber so that the tubing passes through the molten metal during its movement and introducing the coating metal into the chamber in unmelted form during the passage of the tubing through said chamber.

5. The method of brazing multi-ply metal tubing or coating welded tubing with a metal of lower melting point than that of the tubing which includes the steps of moving the tubing through a chamber containing a quantity of the coating metal while maintaining the tubing at a level above the normal level of said metal therein, heating the chamber in which the coating metal is contained, both above and below the level at which the tubing passes through such chamber, by use of a high frequency electric current, to a degree sufficient to melt said metal and to cause the level of the molten metal to rise above the level of the tubing as the latter is moved through the chamber so that the tubing passes through the molten metal during its movement and introducing the coating metal into the chamber in unmelted form during the passage of the tubing through said chamber.

6. The method of brazing multi-ply metal tubing or coating welded tubing with a metal of lower melting point than that of the tubing which comprises the steps of moving the tubing through a chamber which contains a quantity of the coating metal while maintaining the tubing at a level above the normal level of the metal therein while said metal is in a non-molten condition subjecting said chamber to the heating effect of a high frequency electric current so as to heat said chamber to a degree sufficient to melt the coating metal and to cause the level of the molten metal to rise above the level of the tubing as the latter is moved through the chamber, so that the tubing passes through the molten metal during its movement, subjecting the tubing as it leaves the chamber to a blast of non-oxidizing gas directed under pressure against the tubing, at a point relatively close to an opening through which the tubing passes out of the chamber, for the purpose of removing any surplus of the coating metal and introducing the coating metal into the chamber in unmelted form during the coating operation.

7. Apparatus for brazing multi-ply metal tubing and for coating welded tubing with a metal of lower melting point than said tubing comprising, in combination, a chamber in which the tubing and the coating metal are heated, the lower part of which is adapted to contain a supply of the coating metal, openings in the wall of said chamber through which the tube to be coated passes, said openings being located above the normal level of the unmelted coating metal in said vessel so that the tubing passes through said chamber at a point above that level, means for moving the tubing through the chamber during the coating operation, a heating coil surrounding said chamber and connected to a source of electric current of high frequency, said coil being effective to heat said chamber to a degree sufficient to melt the coating metal and to cause the molten metal to rise in said heating chamber to a level above that of the tubing so that the tubing passes through the coating metal as it is moved through said chamber.

8. Apparatus for brazing multi-ply metal tubing and for coating welded tubing with a metal

of lower melting point than said tubing comprising, in combination, a chamber in which the tubing and the coating metal are heated, the lower part of which is adapted to contain a supply of the coating metal, openings in the wall of said chamber through which the tube to be coated passes, said openings being located above the normally level of the unmelted coating metal in said vessel so that the tubing passes through said chamber at a point above that level, means for moving the tubing through the chamber during the coating operation, a heating coil surrounding said chamber and connected to a source of electric current of high frequency, said coil being effective to heat said chamber to a degree sufficient to melt the coating metal and to cause the molten metal to rise in said heating chamber to a level above that of the tubing so that the tubing passes through the coating metal as it is moved through said chamber, and means directing a blast of non-oxidizing gas under pressure against said tubing adjacent the opening through which said tubing passes out of the heating chamber to remove any surplus coating metal.

25. 9. Apparatus for brazing multi-ply metal tubing and for coating welded tubing with a metal of lower melting point than said tubing comprising, in combination, a chamber in which the tubing and the coating metal are heated, the lower part of which is adapted to contain a supply of coating metal, openings in the wall of said chamber through which the tube to be coated passes, said openings being located above the normal level of the unmelted coating metal in said vessel so that the tubing passes through said chamber at a point above that level, means for moving the tubing through the chamber during the coating operation, a heating coil surrounding said chamber and connected to a source of electric current of high frequency, said coil being effective to heat said chamber to a degree sufficient to melt the coating metal and to cause the molten metal to rise in said heating chamber to a level above that of the tubing so that the tubing passes through the coating metal as it is moved through said chamber, and means directing a blast of non-oxidizing gas under pressure against said tubing adjacent the opening through which said tubing passes out of the heating chamber to remove any surplus coating metal.

30. 35. 40. 45. 50. 55. 60. 65. 70. 75. 10. Apparatus for brazing multi-ply metal tubing and for coating welded tubing with a metal of lower melting point than said tubing comprising, in combination, a chamber in which the tubing and the coating metal are heated, the lower part of which is adapted to contain a supply of the coating metal, openings in the wall of said chamber through which the tube to be coated passes, said openings being located above the normal level of the unmelted coating metal in said vessel so that the tubing passes through said chamber at a point above that level, means for moving the tubing through the chamber during the coating operation, a heating coil surrounding said chamber and connected to a source of electric current of high frequency, said coil being effective to heat said chamber to a degree sufficient to melt the coating metal and to cause the molten metal to rise in said heating chamber to a level above that of the tubing so that the tubing passes through the coating metal as it is moved through said chamber, means directing a blast of non-oxidizing gas under pressure against said tubing adjacent the opening through which said tubing passes out of the heating chamber to remove any surplus coating metal, and means for maintaining a sufficient quantity of coating metal within the heating chamber during the coating operation.

15. 20. 25. 30. 35. 40. 45. 50. 55. 60. 65. 70. 75. 10. Apparatus for brazing multi-ply metal tubing and for coating welded tubing with a metal of lower melting point than said tubing comprising, in combination, a chamber in which the tubing and the coating metal are heated, the lower part of which is adapted to contain a supply of the coating metal, openings in the wall of said chamber through which the tube to be coated passes, said openings being located above the normal level of the unmelted coating metal in said vessel so that the tubing passes through said chamber at a point above that level, means for moving the tubing through the chamber during the coating operation, a heating coil surrounding said chamber and connected to a source of electric current of high frequency, said coil being effective to heat said chamber to a degree sufficient to melt the coating metal and to cause the molten metal to rise in said heating chamber to a level above that of the tubing so that the tubing passes through the coating metal as it is moved through said chamber, means directing

a blast of non-oxidizing gas under pressure against said tubing adjacent the opening through which said tubing passes out of the heating chamber to remove any surplus coating metal and means for continuously introducing unmelted casting metal in the heating chamber as the tubing to be coated is drawn through said chamber.

11. Apparatus for brazing multi-ply metal tubing and for coating welded tubing with a metal of lower melting point than said tubing comprising, in combination, a chamber in which the tubing and the coating metal are heated, the lower part of which is adapted to contain a supply of the coating metal, openings in the wall of said chamber through which the tube to be coated passes, said openings being located above the normal level of the unmelted coating metal in said vessel so that the tubing passes through said chamber at a point above that level, means for moving the tubing through the chamber during the coating operation, a heating coil surrounding the lower part of the heating chamber in which the coating metal is contained and connected to a source of electric current of high frequency, said coil being effective to heat said chamber to a degree sufficient to melt the coating metal and to cause the molten metal to rise in said heating chamber to a level above that of the tubing so that the tubing passes through the coating metal as it is moved through said chamber.

12. Apparatus for brazing multi-ply metal tubing and for coating welded tubing with a metal of lower melting point than said tubing comprising, in combination, a chamber in which the tubing and the coating metal are heated, the lower part of which is adapted to contain a supply of the coating metal, openings in the wall of said chamber through which the tube to be coated passes, said openings being located above the normal level of the unmelted coating metal in said vessel so that the tubing passes through said chamber at a point above that level, means for moving the tubing through the chamber during the coating operation, a heating coil connected to a source of electric current of high frequency and surrounding the heating chamber both above and below the level at which the tubing to be coated passes through such chamber, said coil being effective to heat said chamber to a degree sufficient to melt the coating metal and to cause the molten metal to rise in said heating chamber to a level above that of the tubing, so that the tubing passes through the coating metal as it is moved through said chamber.

13. Apparatus for brazing multi-ply metal tubing and for coating welded tubing with a metal of lower melting point than said tubing comprising, in combination, a chamber in which the tubing and the coating metal are heated, the lower part of which is adapted to contain a supply of the coating metal, openings in the wall of said chamber through which the tube to be coated passes, said openings being located above the normal level of the unmelted coating metal in said vessel so that the tubing passes through said chamber at a point above that level, means for moving the tubing through the chamber during the coating operation, a tubular metallic heating coil connected to a source of electric current of high frequency and surrounding the heating chamber, said coil being effective to heat said chamber to a degree sufficient to melt the coating metal and

to cause the molten metal to rise in said heating chamber to a level above that of the tubing so that the tubing passes through the coating metal as it is moved through said chamber and means for circulating a cooling medium through said coil.

14. Apparatus for brazing multi-ply metal tubing and for coating welded tubing with a metal of lower melting point than said tubing comprising, in combination, a chamber in which the tubing and the coating metal are heated, the lower part of which is adapted to contain a supply of the coating metal, openings in the wall of said chamber through which the tube to be coated passes, said openings being located above the normal level of the unmelted coating metal in said vessel so that the tubing passes through said chamber at a point above that level, means for moving the tubing through the chamber during the coating operation, a heating coil connected to a source of electric current of high frequency and surrounding said heating chamber, said coil being effective to heat said chamber to a degree sufficient to melt the coating metal and to cause said molten metal to rise adjacent the vertical axis of said chamber to a level higher than that of the tubing, while the metal adjacent the wall of said chamber remains at a level lower than that of the tubing, whereby the tubing is prevented from passing through the molten coating metal at a point adjacent the opening through which the tubing is moved out of such chamber and the transport of surplus coating metal out of said chamber by the tubing is reduced.

15. Apparatus for brazing multi-ply metal tubing and for coating welded tubing with a metal of lower melting point than said tubing comprising, in combination, a chamber in which the tubing and the coating metal are heated, the lower part of which is adapted to contain a supply of the coating metal, openings in the wall of said chamber through which the tube to be coated passes, said openings being located above the normal level of the unmelted coating metal in said vessel so that the tubing passes through said chamber at a point above that level, means for moving the tubing through the chamber during the coating operation, a heating coil connected to a source of electric current of high frequency and surrounding said heating chamber, said coil being effective to heat said chamber to a degree sufficient to melt the coating metal and to cause said molten metal to rise adjacent the vertical axis of said chamber to a level higher than that of the tubing, while the metal adjacent the wall of said chamber remains at a level lower than that of the tubing, whereby the tubing is prevented from passing through the molten coating metal at a point adjacent the opening through which the tubing is moved out of such chamber and the transport of surplus coating metal out of said chamber by the tubing is reduced, and means for directing a blast of non-oxidizing gas under pressure against the tubing adjacent said last mentioned opening and in a direction substantially opposite to the direction of movement of the tubing in order to minimize the escape of the coating metal through said opening as the tubing is moved therethrough.

16. Apparatus for brazing multi-ply metal tubing and for coating welded tubing with a metal of lower melting point than said tubing comprising, in combination, a chamber in which the tubing and the coating metal are heated, the

lower part of which is adapted to contain a supply of the coating metal, openings in the wall of said chamber through which the tube to be coated passes, said openings being located above the normal level of the unmelted coating metal in said vessel so that the tubing passes through said chamber at a point above that level, means for moving the tubing through the chamber during the coating operation, a heating coil connected to a source of electric current of high frequency and surrounding said heating chamber, said coil being effective to heat said chamber to a degree sufficient to melt the coating metal and to cause said molten metal to rise adjacent the vertical axis of said chamber to a level higher than that of the tubing, while the metal adjacent the wall of said chamber remains at a level lower than that of the tubing, whereby the tubing is prevented from passing through the molten coating metal at a point adjacent the opening through which the tubing is moved out of such chamber and the transport of surplus coating metal out of said chamber by the tubing is reduced and a nozzle for directing a blast of non-oxidizing gas against the tubing adjacent said last mentioned opening, said nozzle being arranged at an angle to the path of movement of the tubing and discharging said gas in a direction substantially opposite to the direction of movement of the tubing, in order to minimize the escape of coating metal through said opening as the tubing is moved therethrough.

17. Apparatus for brazing multi-ply metal tubing and for coating welded tubing with a metal of lower melting point than said tubing comprising, in combination, a chamber in which the tubing and the coating metal are heated, the lower part of which is adapted to contain a supply of the coating metal, openings in the wall of said chamber through which the tube to be coated passes, said openings being located above the normal level of the unmelted coating metal in said vessel so that the tubing passes through said chamber at a point above that level, means for moving the tubing through the chamber during the coating operation, a heating coil surrounding said heating chamber and connected to a source of electric current of substantially 960 cycles frequency, said coil being effective

5 to heat said chamber to a degree sufficient to melt the coating metal and to cause the molten metal to rise in said heating chamber to a level above that of the tubing so that the tubing passes through the coating metal as it is moved through said chamber.

18. Apparatus for brazing multi-ply metal tubing and for coating welded tubing with a metal of lower melting point than said tubing comprising, in combination, a chamber in which the tubing and the coating metal are heated, the lower part of which is adapted to contain a supply of the coating metal, openings in the wall of said chamber through which the tube to be coated passes, said openings being located above the normal level of the unmelted coating metal in said vessel so that the tubing passes through said chamber at a point above that level, means for moving the tubing through the chamber during the coating operation, a heating coil surrounding said chamber and connected to a source of electric current of high frequency, said coil being effective to heat said chamber to a degree sufficient to melt the coating metal and to cause the molten metal to rise in said heating chamber to a level above that of the tubing so that the tubing passes through the coating metal as it is moved through said chamber, said heating chamber having an opening in the wall thereof adapted to receive a wire formed of the coating metal which is moved into the chamber during the coating operation so as to maintain a predetermined quantity of the coating metal in said chamber.
